UNITED STATES PATENT OFFICE

ENOCH RECTOR, OF NEW YORK, N. Y., ASSIGNOR TO WAUKESHA MOTOR COMPANY, OF WAUKESHA, WISCONSIN, A CORPORATION OF WISCONSIN

NATURAL GAS CARBURETOR

Application filed October 27, 1928. Serial No. 315,470.

This invention relates to carburetors, and more particularly to a carburetor adapted for use with either natural or artificial gas.

One of the main objects of my invention is to provide a carburetor of simple construction and operation in which the gas and the air are effectively commingled and the gas is metered in such manner as to assure proper proportioning of the gas to the air for all engine speeds. Further objects and advantages of my invention will appear from the detailed description.

In the drawings:

Fig. 1 is a central vertical sectional view through a gas carburetor in accordance with my invention, parts being shown in elevation, also illustrating the method of using a liquid fuel carburetor in combination with my gas carburetor, when desired;

Fig. 2 is a horizontal sectional view taken substantially on line 2—2 of Fig. 1.

The carburetor includes a main body or casing 1 which is illustrated as being formed in one piece, though this body may be formed in several sections if desired. The body 1 includes a stack 2, the lower portion of which is shaped to provide a Venturi element 3. A mixing chamber 4 is provided beneath stack 2 and has communication therewith through a fuel mixture outlet opening 5 at the top of the chamber, this opening constituting the lower end of the Venturi element 3. A gas chamber 6 is provided below the mixing chamber 4 and a dash pot 7 is provided below the gas chamber. This dash pot is of known type and includes a cylinder 8 which is suitably secured to the lower end of body 1, and a plunger 9 which fits loosely within the cylinder for reciprocation therein.

A plug 10 is suitably secured through the central portion of the bottom wall of gas chamber 6, as by threaded engagement therewith. This plug is provided, at its lower end, with an outer peripheral flange 11 which fits snugly in the upper end of cylinder 8 and is secured in a suitable manner, as by a screw 12, to the bottom wall of the gas chamber. The plug 10 is provided with a gas inlet tube 13 extending upwardly therefrom and fitting snugly through a central opening 14

in the bottom wall 15 of the mixing chamber. Gas is admitted to the annular space 16 about the lower portion of tube 13 by means of a gas supply pipe 17, and this gas enters tube 13 through openings 18 in the lower portion thereof.

The gas inlet tube 13 is provided, in its upper portion, with a plurality of radially disposed slots 19 extending lengthwise of the tube. A sleeve 20 fits snugly above the upper portion of the tube for turning movement thereon, this sleeve being provided with slots 21 corresponding to the slots 19 of the tube. The sleeve is of a length to extend above and below the slots of the tube and is provided with a radially projecting arm 22 which extends through a slotted supporting and guide element 23 formed integrally with the wall of mixing chamber 4. Set screws 24 are threaded in the end walls of the element 23 and contact arm 22 at opposite sides thereof, these screws being held in adjustment by jam nuts 25. By turning the sleeve 20 upon the upper portion of tube 13 direct communication between the mixing chamber and the tube, through the slots 19, is established, and the effective size of these slots can be adjusted to suit conditions. After being adjusted the sleeve is secured in adjustment by the set screws 24 and associated parts.

As will be noted more clearly from Fig. 2, the mixing space 4a of chamber 4 is of substantially annular shape and is concentric with the gas inlet tube. This chamber is provided with a radially disposed nipple 26 adapted for reception of the end portion of an air inlet pipe or tube, this nipple having an inner circumferential flange defining an air inlet opening 27. A baffle 28 is suitably secured on sleeve 20 in spaced relation thereto, this baffle being disposed in front of the inlet opening 27 so that the entering air stream will be deflected and the air caused to circulate about the annular mixing space 4a without disturbing the proper flow of gas through the gas inlet or admission openings of the tube 13.

Flow of the mixture of gas and air through the outlet opening 5 is controlled by an up-

wardly opening suction responsive valve 29 which, in its lowermost position, closes opening 5. This valve is provided with a depending stem 30 which extends downwardly 5 through the tube 13 and plug 10 into cylinder 8 of the dash pot. Valve stem 30 is reduced and threaded at its lower end to provide a screw stud 31 and a shoulder 32 at the upper end of this stud. The stud 31 10 passes through plunger 9 of the dash pot, this plunger being provided with a central recesses 9a to accommodate a nut 33 screwed onto the stud 31 and serving therewith to secure the plunger to the lower end of the 15 valve stem. The plunger 9 thus constitutes a counterweight which urges the valve 29 in closing direction. A gas metering valve 34 is formed integrally with, or otherwise suitably secured to, the valve stem 30 and has a 20 sliding fit within the upper slotted portion of tube 13. When the fuel valve 29 is in its lowermost position, the metering valve 34 is disposed adjacent the lower ends of slots 19 so as to substantially cut off communication 25 between the gas inlet tube 13 and the mixing chamber. This valve 34 also serves, in conjunction with the tube 13, to guide the valve stem 30 during vertical reciprocation thereof. The valve stem is a sliding fit 30 through plug 10 which coats with the valve 34 and associated parts to prevent any undesirable looseness or play of valve stem 30. A throttle valve 35 is mounted in stack 2 above the Venturi element 3. This valve 35 functions and is operated in a known manner. A gasoline carburetor 36 of known type has communication with stack 2, through a suitable connection 37 and a priming fuel inlet opening 38 disposed above the throttle 40 valve 35. Communication between the carburetor 36 and stack 2 may be controlled in any suitable manner, as by means of a throttle valve (not shown) in the connection 37. 45 The function of the gasoline carburetor 36 is to start the engine to which the gas carburetor is connected, in a known manner, by means of a suitable flange 39 at the upper end of stack 2, this flange being secured to 50 the intake manifold of the engine. After the engine has been started, with the throttle valve 35 closed as illustrated in Fig. 1, the carburetor 36 is then cut off from the stack 2 and the throttle valve 35 is opened so as to connect the gas carburetor to the engine. A set screw 40 is threaded through a collar 41 at the bottom of cylinder 8 of the dash pot and is secured in adjustment by a jam nut 42. This set screw contacts the lower 60 end of valve stem 30 and limits downward movement of valve 29 and the gas metering valve 34. The adjustment of this set screw determines the amount of gas which flows through the slots 19 into the mixing chamber 4 when the throttle valve 35 is first opened.

By adjusting the set screw 40 and the sleeve 20 the proper proportion of gas to the volume of air entering the mixing chamber 4 can be obtained. In this manner, the fuel mixture can be readily regulated to suit conditions and assure maximum efficiency. During operation of the engine, the valve 29 is raised and lowered by the combined action of the suction of the engine and the counterweight 9 and in accordance with variations in engine speed. This raising and lowering of the valve 29 results in similar movement of the valve 34 so that the gas supplied to the mixing chamber is metered by valve 34, the effective area of the slots 19 being increased and decreased in accordance with opening and closing of valve 29. This assures proper proportioning of the gas and air of the fuel mixture for all engine speeds with resulting high efficiency in operation. 85

What I claim is:

1. In a gas carburetor a stack, a substantially annular and fixed mixing chamber opening into the stack and having a radial air inlet opening, a fixed gas inlet tube extending into the chamber axially thereof and having elongated radial openings normally in direct communication with the chamber for admitting gas directly thereto, a suction responsive valve controlling the flow of air and gas from the chamber to the stack, and a member movable with the valve and controlling the effective area of the gas admission openings in accordance with opening and closing of said valve. 95

2. In a gas carburetor, a substantially annular and fixed mixing chamber having a radial air inlet opening, a stack above the chamber and communicating with said chamber at the top thereof through a fuel mixture outlet opening, a suction responsive valve controlling said opening, a fixed gas inlet tube extending into the chamber axially thereof and having radial openings normally in direct communication with the chamber, and a member movable with the valve and having a sliding fit with the tube and controlling the effective area of the gas admission openings in accordance with opening and closing of said valve. 105

3. In a gas carburetor, a mixing chamber having an air inlet opening and a fuel mixture outlet opening, a gas inlet tube having openings for admitting gas to the chamber, a suction responsive fuel mixture valve controlling said opening, fuel supply means including a gas inlet tube having openings for admitting gas to the chamber, a member movable with the valve and having a sliding fit with the tube and controlling the effective area of said gas admission openings in accordance with opening and closing of said valve, and a dash pot including a plunger connected to the valve and constituting a counterweight urging the valve in closing 130

- direction, said dash pot being separate from the fuel supply means.
4. In a gas carburetor, a mixing chamber having an air inlet opening, a stack above the chamber and communicating with the chamber through a fuel mixture outlet opening at the top of the chamber, a gas inlet tube extending into the chamber in the direction of said outlet opening and provided with 5 slots extending lengthwise of the tube and opening into the chamber for admitting gas thereto, a suction responsive fuel mixture valve controlling the outlet opening and having a depending stem extending into the tube, a gas metering valve carried by said stem and contacting the circumferential surface of the tube adjacent the gas admission slots for controlling the effective area of the slots in accordance with closing and opening 10 of the fuel control valve, and a dash pot including a plunger secured to the valve stem and constituting a counterweight urging the fuel mixture valve in closing direction.
5. In a gas carburetor, a substantially 15 annular and fixed mixing chamber having a radial air inlet opening, a stack above the chamber, said chamber having a fuel mixture outlet opening at the top thereof communicating with the stack, a fixed gas inlet tube projecting into the chamber axially thereof and having radially disposed elongated slots extending lengthwise thereof and normally opening directly into the chamber, a suction responsive fuel mixture valve controlling 20 said opening, said valve having a depending stem extending into the tube, and a gas metering valve carried by the valve stem and fitting the interior of the slotted portion of the tube, said metering valve varying the effective area of the slots in accordance with opening and closing of the fuel mixture valve.
6. In a gas carburetor, a fixed mixing chamber having an air inlet opening and a fuel mixture outlet opening, a fixed gas inlet 25 tube projecting upwardly within the mixing chamber and having radially disposed elongated slots extending lengthwise thereof, a suction responsive fuel mixture valve controlling said opening and having a depending stem extending into the tube, and a gas metering valve carried by the valve stem and fitting within the slotted portion of the tube, said metering valve controlling the effective area of the slots in accordance with opening 30 and closing of the fuel mixture valve.
7. In a gas carburetor, a mixing chamber having an air inlet opening and a fuel mixture outlet opening, a gas inlet tube extending into the chamber and having radially disposed elongated slots extending lengthwise thereof, a sleeve fitting about the slotted portion of the tube and correspondingly slotted, means for adjusting the sleeve about the tube to vary the effective size of the tube slots, a fuel mixture valve controlling said outlet 35 opening and having a depending stem extending into the tube, and a gas metering valve carried by the valve stem and fitting into the slotted portion of the tube, said gas metering valve varying the effective area of the tube slots in accordance with opening and closing of the fuel mixture valve.
8. In a carburetor, a substantially annular mixing chamber having a radial air inlet opening and provided in its top with a fuel mixture outlet opening, a gas inlet tube extending into the chamber and having radially disposed slots extending lengthwise thereof, a sleeve fitting about the slotted portion of the tube and correspondingly slotted, means for adjusting the sleeve about the tube to vary the effective size of the tube slots, a baffle secured to the sleeve in spaced relation thereto and disposed in front of the air inlet opening, a fuel mixture valve controlling said outlet opening and having a depending stem extending into the tube, and a gas metering valve carried by the valve stem and fitting into the slotted portion of the tube, said gas metering valve increasing and decreasing the effective area of the tube slots in accordance with opening and closing of the fuel mixture valve.
9. In a gas carburetor, a mixing chamber having an air inlet opening, a stack above the chamber and communicating therewith through a fuel mixture outlet opening at the top of the chamber, a gas chamber below the mixing chamber, a gas inlet tube opening into the gas chamber and extending upwardly into the mixing chamber, said tube having radially disposed slots extending lengthwise thereof and opening directly into the mixing chamber, a suction responsive valve controlling said outlet opening and having a depending stem extending into the tube, a gas metering valve carried by the valve stem and fitting into the slotted portion of the tube, said metering valve increasing and decreasing the effective area of the gas admission slots in accordance with opening and closing of the fuel mixture valve, and a dash pot below the gas chamber including a plunger, the valve stem extending into the dash pot and the plunger being secured on the stem and constituting a counterweight urging the fuel mixture valve in closing direction.
10. In a gas carburetor, a mixing chamber, a stack above the chamber and communicating therewith through a fuel mixture outlet opening, a gas chamber below the mixing chamber, a plug secured in the bottom wall of the gas chamber and having a gas inlet tube opening into said gas chamber and extending into the mixing chamber, the portion of the tube within the mixing chamber having radially disposed slots extending lengthwise thereof and opening directly into said mixing chamber, a dash pot below the gas chamber and including a plunger, a suc-

- tion responsive fuel mixture valve controlling said outlet opening, said valve having a depending stem extending through the gas tube and slidable through said plug, the
- 5 plunger being secured to the valve stem and constituting a counterweight urging the fuel mixture valve in closing direction, and a gas metering valve carried by said valve stem and having a sliding fit within the slotted
- 10 portion of the tube, said metering valve acting to increase and decrease the effective area of the gas admission slots in accordance with opening and closing of the fuel mixture valve.
- 15 11. In combination, a stack, a mixing chamber opening into the stack, a suction responsive valve controlling communication between the stack and the chamber, means for supplying air and gas to said chamber, a
- 20 throttle valve in the stack, and a liquid fuel carburetor communicating with the stack between the outlet end thereof and the throttle valve.
12. In combination, a stack, a mixing chamber opening into the stack and provided with an air admission opening, a gas inlet tube extending into the chamber axially thereof and having elongated slots opening into said chamber, means for supplying
- 25 30 gas to the tube, a suction responsive valve controlling communication between the chamber and the stack, a gas metering valve carried by the suction responsive valve and having a sliding fit with the tube and controlling the effective size of the slots thereof, a throttle valve in the stack, and a liquid fuel carburetor communicating with the stack between the outlet end thereof and the throttle valve.
- 35 40 13. In a gas carburetor, a stack, a fixed mixing chamber opening into the stack and provided with an air inlet opening, a fixed gas inlet tube extending into the chamber and having slots extending lengthwise thereof, a suction responsive valve controlling communication between the stack and the chamber and provided with a stem extending into the tube, and a gas metering valve carried by the valve stem and fitting into the
- 45 50 slotted portion of the tube and controlling the effective area of said slots.

In witness whereof, I hereunto subscribe my name this 18th day of October, 1928.

ENOCH RECTOR.
